UNITED STATES PATENT OFFICE.

EDWARD P. SHELDON, OF NEW YORK, N. Y., ASSIGNOR TO R. HOE AND CO., OF NEW YORK, N. Y., A CORPORATION OF NEW YORK.

ROTARY SHEET-PRINTING MACHINE.

1,078,963.

Specification of Letters Patent.

Patented Nov. 18, 1913.

Application filed February 5, 1910. Serial No. 542,180.

To all whom it may concern:

Be it known that I, EDWARD P. SHELDON, a citizen of the United States, residing at New York, county of Kings, and State of New York, have invented certain new and useful Improvements in Rotary Sheet-Printing Machines, fully described and represented in the following specification and the accompanying drawings, forming a part of 10 the same.

This invention relates to certain improvements in printing machines.

The invention has for its object to produce a high speed sheet-fed printing machine in which accurate register of the sheets is maintained and which is capacitated to produce a large product.

With this and other objects not specifically referred to in view, the invention consists 20 in certain constructions and in certain parts, improvements and combinations as will be hereinafter fully described and then specifically pointed out.

Referring to the accompanying drawings:—Figure 1 is a diagrammatic view illustrating one form of mechanism in which the invention may be embodied. Fig. 2 is a plan view of one end of a sheet carrying cylinder, illustrating more particularly a 30 form of gripper operating mechanism which may be employed. Fig. 3 is a sectional view illustrating the gripper operating mechanism shown in Fig. 2. Figs. 4 and 5 are diagrammatic views illustrating the sheet 35 feeding operation. Fig. 6 is a detail view illustrating a mechanism for delivering the sheets which may be employed. Fig. 7 is a sectional view taken on the line 7—7 of Fig. 3. Figs. 8, 9 and 10 are detail views illustrating the operation of the sheet taking 40 mechanism.

Referring to the drawings which illustrate a machine selected as one embodiment of the invention, 1 indicates the sheet carrying or impression cylinder of a rotary printing couple, said cylinder being mounted on a shaft 2. The co-operating member of the couple consists, in the machine illustrated, of a printing cylinder 3 mounted 50 on a shaft 4, the cylinder deriving its ink from an inking battery or mechanism 5 of the usual type. While the sheets printed by this couple may be delivered in any desired way, in the machine shown, they are

delivered by means of the delivery cylinder 55 6 mounted on a shaft 7.

Machines embodying the invention are intended to print on sheets and the construction will be such that the sheets will be fed to the sheet carrying cylinder of the couple 60 at separated but closely adjacent points. The sheet feeding mechanism employed may be varied widely in construction. As shown, the sheets are fed from two automatically operated sheet feeders, the sheet supporting 65 tables of which are marked 9 and 10. The sheets from these tables are combed out and fed forward by cylinders 11 and are eventually delivered to tape rolls, indicated at 12, 13. The particular construction by which 70 the sheets are fed has no relation to the invention, and the particular construction of sheet feeding mechanism does not, therefore, need to be specifically described. The illustration is intended simply to indicate dia- 75 grammatically that automatic sheet feeders may be employed, though, of course, it is obvious that sheets might be fed by hand, if desired. In the particular construction illustrated, the sheets move through pathways, the 80 upper pathway being indicated by the rolls 14 and the lower pathway by the rolls 15, 16, to the sheet taking devices on the cylinder 1. These pathways will be arranged to deliver the sheets to the cylinder at points 85 which are separated from each other but closely adjacent, this being effected, in the particular construction illustrated, by causing the pathways to converge. While the 90 distance apart at which the sheets are delivered may vary, they should be delivered within the same quadrant of the revolution of the cylinder. In the best constructions involving the invention, the sheets will be brought to register before being taking by 95 the sheet taking cylinder. While this registering operation may be accomplished in various ways, as shown, the upper pathway delivers to sheet registering stops 17 and the lower pathway to sheet registering stops 18. 100 These stops may be of the usual type well-known in the art, and a specific description of their construction and mode of operation is, therefore, unnecessary.

The sheet taking devices employed may be 105 varied in construction, but in machines which embody the invention in its best form, these devices will consist of grippers. When

grippers are employed as sheet taking devices, their construction and the construction of the operating devices therefor may be varied within wide limits. As shown, these grippers, marked 19, are mounted on a shaft 20 carried in arms 21 mounted on a rock-shaft 22 journaled in the ends of the cylinder. This rock-shaft, in the particular construction shown, is provided with 10 an operating arm 23 carrying a stud or roll 24. The shaft 20 is, in the particular construction illustrated, provided with an operating arm 25 which carries a stud or roll 26. As shown, the shaft 20 is also provided with another operating arm, shown as 15 a toothed segment 27 which meshes with a similar segment 28 mounted on a stud 29, this segment having an operating arm 30 to which a spring rod construction 31 of the 20 usual type is connected.

Where, as in the machine shown, a single set of sheet taking devices is employed to take sheets at different points of the revolution of the cylinder, it is necessary, of 25 course, to provide means for effecting the sheet taking operation at these different points. This may be accomplished in various ways. In the particular construction illustrated, the operating devices include 30 cams which have their positions shifted or varied to effect the sheet taking operation. As shown, the roll 26 coöperates with a cam 32 bolted or otherwise secured to a segment shaped piece 33 extending from a collar 34, 35 loosely mounted on the shaft 2 of the cylinder 1. The roll 24 coöperates with a two-part cam 35—36, the part 36 being provided with feet 37 (see Figs. 2 and 7) by which it is secured to the frame of the machine. 40 The part 35 of the cam is secured by a screw 38, or in any other suitable manner, to the segment shaped piece 33 before referred to. It will be understood that the roll 24 is broad enough to run on both parts 35, 36 45 of the cam. It is obvious that by swinging the collar 34 and the segment shaped piece 33 about the shaft, the position of the operating cams 32, 35 may be varied. The swinging of the segment shaped piece 33, 50 when this form of mechanism is adopted for carrying the invention into effect, may be accomplished by any suitable mechanism. In the construction illustrated, there is provided a two-armed lever 43—44 loosely 55 mounted on the shaft 2. The hub of the two-armed lever 43—44 is provided with teeth 47 which mesh with teeth on a segment 48 fast on a short shaft 49 mounted in the frame of the machine. This shaft 49 has a 60 toothed segment 50 mounted thereon, the teeth of which mesh with teeth 51 formed on one of the arms 52 of a bell-crank lever 52—53, this lever being pivoted on a stud 54 mounted in the machine frame. The arm 65 53 is provided with a roll 55 which runs in

the groove 56 in a cam 57, mounted on the cylinder shaft 2 and suitably driven. The arm 44 of the two-armed lever has connected to it a spring rod construction, the rod 58 of this construction passing through a 70 boss 58' on the arm 44 and being provided with nuts 58''. The other end of this rod is secured at 59 to the segment shaped piece 33 before referred to.

With the construction as described and 75 referring to Fig. 8, at which time the grippers are about to take a sheet from the stop 17, it will be seen that the roll 24 is about to run off the cam 35 and that the roll 26 is about to run up onto the cam 32. When the 80 roll 24 has run off the cam 35 and the roll 26 has run up onto the cam 32, the grippers 19 will be raised out of the cylinder and into taking position, as illustrated in Fig. 3, this operation being permitted by reason of 85 the fact that the ends of the shaft 20 on which these grippers are mounted are located in slots 60 in the ends of the cylinder. As the roll 26 runs off the cam 32, the spring rod construction 31 causes the grippers to 90 snap down into the position shown in Fig. 9, and thus close upon the sheet, the stop 17 being raised, as usual, in sheet feeding constructions, to permit the sheet to be taken.

It will be understood that the grippers 95 must operate very quickly and to avoid making the gripper operating cam too abrupt, it may be desirable to move the cam from under the roll 26, thereby permitting a quicker action of the grippers than if the 100 rotation of the cylinder was allowed to carry the roll 26 off the cam. To effect this there may be provided a collar 34 having teeth 39, these teeth meshing with teeth 40 on a bell-crank lever 41—42 pivoted on a stud 42' 105 fast on the arm 43 of the two-armed lever 43—44. The arm 42 carries a roll 45 arranged to contact with a cam 46 fast on the cylinder. As the roll 26 reaches the high part of the cam 32, the high part of the cam 110 46 which is fast on the cylinder strikes the roll 45 and rocks the bell-crank lever 41—42 which gives the collar 34 a slight rotating movement which causes the segment shaped piece 33 to move backward slightly with respect to the direction of rotation of the cylinder, this movement carrying the cam 32 out from under the roll 26, thus assuring a very quick action of the grippers. The 115 movement of the collar 34 is resisted by the spring rod construction 58 before referred to, which returns the parts to their normal position after the grippers have closed. The sheet is now carried around, printed and delivered. The delivery of the sheet may be 120 effected in any suitable manner. In the particular construction shown (see Figs. 1 and 6) it is delivered, as before indicated, by a delivery cylinder 6, this cylinder being provided with grippers 61 which take the 125 130

leading end of the sheet. The grippers 19 are opened by a cam 62 fast to the part 36 of the two part cam 35-36. After the grippers are opened to release the sheet, they are drawn back into the cylinder by a cam surface 63 formed on the lower end of the part 36 of the two-part cam. This surface 63 operates with the roll 24. The grippers are now to take a sheet from the stop 18, but in order to do this, it is apparent that they must be opened earlier in the revolution of the cylinder than they were when they took the sheet from the stop 17. The cam 57 accordingly comes into operation and rocks the lever 52-53 which, through the connections before described, rocks the shaft 49 and the toothed segment 48 which is in mesh with the teeth 47 on the hub of the two-armed lever 43-44 and swings this lever about the shaft 2 from the position shown in Fig. 3 to the position shown in Fig. 10. The rod of the spring rod construction which has been heretofore described as connecting the arm 44 and the segment shaped piece 33 draws this piece, carrying the cam 32 and the part 35 of the two-part cam 35-36, backward with respect to the rotation of the cylinder into the position shown in Fig. 10. In this position, it will be apparent that the rolls 24 and 26 will operate earlier with the cams 32, 35-36, and the same is true of the quickening bell-crank 41-42. A sheet will, therefore, be taken from the stop 18. The sheet is taken, carried forward, printed and delivered, after which the shifting mechanism for the gripper operating cam comes into operation and brings this operating mechanism back into the position shown in Fig. 3, thus enabling the next sheet to be taken from the stop 17.

In the particular construction illustrated, it is desirable to feed the sheets to the cylinder in such a manner that the sheets from one source will not interfere with the taking of the sheets from the other source. In the particular construction illustrated, this is accomplished by timing the action of the feeders, so that the sheets are sent away from the tables alternately with respect to each other, as indicated in Figs. 4 and 5. In these figures, the sheets from the upper source or table are indicated by the broken lines and the sheets from the lower source or table are indicated by the full lines.

Referring to Fig. 4, it will be noted that the cylinder 1 has taken a sheet from the upper surface which has been carried around and partially printed and is ready for delivery by the cylinder 6, and the sheet from the lower source has come into position ready to be taken by the grippers. In Fig. 5, the sheet from the lower source has been taken by the cylinder 1 and is being carried around and the sheet from the upper source

has come into position to be taken by the grippers. The sheets are timed in such a way that each sheet is at rest during the time it takes half the length of the preceding sheet to pass around the cylinder. This gives sufficient time to insure the accurate register of the sheets against the stops 17, 18. It will be understood that in many machines of this character, the register must be practically absolutely exact, that is, within what is known as a "hair line." By feeding and bringing the sheets to rest against the stops in the manner described, time for this accurate register is obtained and is obtained without interfering with the rapidity of the sheet feeding operation. Further, the sheets may follow each other around the cylinder with practically no space between them, so that the entire surface of the cylinder, except for the width of the gap through which the grippers operate, may be occupied, if desired, by plates. This enables sheets which are substantially equal in length to the circumference of the cylinder to be printed, or, as stated in another way, it enables a cylinder to be employed the circumference of which is substantially no greater than the length of the printing plates it is desired to employ. Further, by employing a plurality of feeds a very large product can be obtained. In fact, the speed of the cylinder need be limited only by its capacity to produce the character of work desired.

Changes and variations may be made in the construction by which the invention is carried into effect. The invention is not, therefore, to be confined to the particular construction herein shown and described.

What is claimed is:—

1. The combination with the sheet carrying cylinder of a printing couple, of means for delivering sheets from different sources to the same sheet carrying surface on the cylinder at different but closely adjacent points, sheet taking devices on the cylinder, and means for causing said devices to take the sheets at said points.

2. The combination with the sheet carrying cylinder of a printing couple, of means for delivering sheets from different sources to the same sheet carrying surface on the cylinder at different but closely adjacent points, grippers on the cylinder, operating devices therefor, and means for effecting the operation of said devices to cause the grippers to take the sheets at said points.

3. The combination with the sheet carrying cylinder of a printing couple, of means for delivering sheets from different sources to the same sheet carrying surface on the cylinder at different but closely adjacent points, grippers on the cylinder, means including an actuator for operating the grippers, and means for causing the actuator

4
to operate the grippers to take the sheets at said points.

4. The combination with a rotary printing couple, of means for delivering sheets in succession from different sources to one of the cylinders at different but closely adjacent points, a single set of sheet taking devices, and means for operating the sheet taking devices to cause them to take the sheets at one point on one revolution of the cylinder, and at the other points on the succeeding revolutions of the cylinder.

5. The combination with a rotary printing couple, of means for delivering sheets in succession from different sources to one

of the cylinders at different but closely adjacent points, a single set of sheet taking grippers, and means for operating the sheet taking grippers to cause them to take the sheets at one point on one revolution of the cylinder, and at the other points on the succeeding revolutions of the cylinder.

In testimony whereof, I have hereunto set my hand, in the presence of two subscribing witnesses.

EDWARD P. SHELDON.
